UNITED STATES PATENT OFFICE.

NIELS C. SUND, OF CHICAGO, ILLINOIS.

STOP-COCK BOX.

SPECIFICATION forming part of Letters Patent No. 514,633, dated February 13, 1894.

Application filed September 26, 1893. Serial No. 486,532. (No model.)

To all whom it may concern:

Be it known that I, NIELS C. SUND, a citizen of the United States, residing at Chicago, in the county of Cook and State of Illinois, 5 have invented a new and useful Improvement in Stop-Cock Boxes, of which the following is a specification.

My invention relates to improvements in boxes for the stop-cocks of service-pipes, and 10 more especially to the class of stop-cock boxes formed of extensible members and in which the lower member is provided with an enlarged foot or base-portion, to house the stop-cock, and provided at opposite sides with slots 15 through which the service-pipe may extend.

While stop-cock boxes of the class described are quite generally regarded as the most desirable for their purpose, it is found in their use that as constructed they present 20 objectionable features which it is desirable to overcome. For example, when the box is placed in a sandy soil it happens frequently that the sand will work its way up around the stop-cock into the box, making it a difficult 25 matter to get at the cock with a turning-rod or key. Disturbance of the surrounding soil, due to the action of frost or to digging operations in the immediate vicinity, will sometimes cause the box to become tipped, so that 30 the plug cannot be turned with a key, or to become separated from the stop-cock so that the latter is inaccessible; and even if the stop-cock can, when separated from the box, be reached with a key, there is danger that in 35 endeavoring to turn the plug, the service-pipe, usually of lead, will become fractured.

It is my object to provide a stop-cock box of an improved construction, which, while presenting all the advantages of boxes of the 40 class described, will be free from the objectionable features mentioned.

In the drawings—Figure 1 is a view in elevation, partly broken, of the stop-cock box; Fig. 2, an enlarged section taken on line 2 of Fig. 45 1; Fig. 3 an enlarged plan view of the upper end of the box; Fig. 4, an enlarged plan-view of the under side of the cover; Fig. 5, an enlarged broken sectional view of the base or foot portion of the box, showing a stop-cock 50 in position and partly in section; and Fig. 6 a section taken on line 6 of Fig. 5, and viewed in the direction of the arrow.

A is the upper member and A' the lower member of a stop-cock box, which may be rendered extensible in the common manner 55 shown or in any other desirable way. The upper end of the member A is formed with an outer annular recess t affording a seat for the annular flanged rim of a cover s. On the inner side of the said member near the top 60 are flanges r presenting horizontal surfaces, r' , on their under sides, and recesses r^2 . The cover s is provided on its upper side with a central socket s' , at the center of which is an opening through which passes a square-headed 65 bolt q. On the under surface of the cover is a stop preferably in the form of two downward extending ears s^2 at opposite sides of the opening. The shank of the bolt q is threaded and passes through a central 70 threaded opening in a clamping-bar q' which extends between the ears s^2 and is supported by the bolt. At the lower end portion of the bolt is a pin q^2 which prevents separation of the bar from the bolt. To fix the cover upon 75 the box the bolt q is first turned to cause the bar q' to recede from the under side of the cover, and in placing the latter in position the ends of the bar q' are caused to pass down through the recesses r^2 to a plane below the 80 surfaces r' . The cover is then turned to the right or left causing the ears s^2 to engage and turn the bar q' until its ends pass beneath the surfaces r' . A suitable key may then be applied to the bolt to turn the latter and clamp 85 the ends of the bar against the surfaces r' whereby the cover is held tightly in place. The cover may be quickly placed in position or removed, and affords an effective safeguard against the access to the box of dust or moisture. 90

The member A' has a tubular body portion and an expanded foot or base portion A², comprising the enlarged cylindrical part p, with slots p', outer vertical ribs p², and base flanges 95 p³. This is a common construction, and is the construction I prefer to employ, because it is easy to cast, affords a base of comparatively large area, and a convenient means for housing the stop-cock; I do not, however, limit my invention to use with the exact construction illustrated. To carry out my invention I provide on the inner side of the cylindrical part p, a pair of vertical diametrically opposed 100

tongues or ribs p^4 , in a plane, preferably, at right angles to the plane of the slots p' .

B is a stop-cock which may be of the usual plug-valve construction. Toward the top of the valve-shell I provide a head n in the form of an annular flange, provided with diametrically opposed grooves or recesses n' . The shells of service-pipe stop-cocks are frequently provided with screw-threads at their upper end-ports, as shown in Fig. 5, and the heads n to be employed with such stop-cocks may be in the form of internally threaded rings to be screwed upon the valve-shells, as shown, or fastened thereto in any other suitable manner. In the preferred construction, however, the head n is cast integral with the valve-shell. The head or flange n fits loosely into the part p , of the base portion A^2 but is of greater diameter than the main tubular portion of the box, and its grooves n' , which are at a right-angle to the service-pipe x , are adapted to engage the tongues p^4 . In practice the head n fits against the annular shoulder p^5 , at the top of the part p , and closes the lower end portion of the box, in a manner to prevent sand from working its way up into the box, but not so effectively as to prevent any water which may leak from the valve from running out. It frequently happens that the plug of a service-cock becomes worn and loose, and permits water to escape into the box; and if the water thus escaping cannot run out of the box it is apt to freeze in winter and render the plug inaccessible. The engagement of the head n with the tongues p^4 prevents relative displacement between the box and stop-cock, therefore in the event that the box becomes tipped the plug will always be accessible.

40 Although I prefer to construct the parts as

shown and described with recesses or grooves n' in the head n and ribs or tongues p^4 in the base-portion A^2 of the box, it is obvious that grooves could be formed in the said base-portion to receive tongues formed upon the head n 45 and the effect would be to all intents and purposes the same.

The construction may be further modified in the matter of details without departing from the spirit of my invention as defined by the claims.

What I claim as new, and desire to secure by Letters Patent, is—

1. In combination, a stop cock box having a tubular body-portion and an expanded base A^2 provided with slots p' , and a stop cock fitting into the said slots, to be housed by the base, and provided with a flange n to enter the said base and close the lower end of the tubular body-portion of the box, substantially as and for the purpose set forth.

2. The combination with a stop-cock and stop-cock box, provided with a base A^2 in which the stop-cock is housed, of a head on the stop-cock closing the lower end-portion of the said box, and a tongue and groove connection between said head and base, substantially as described.

3. The combination with a stop-cock and stop-cock box, provided with a base A^2 in which the stop-cock is housed, of a head n on the stop-cock, to close the lower end-portion of said box, provided with a groove n' , and a tongue p^4 in the said base engaging the said groove substantially as described.

NIELS C. SUND.

In presence of—
M. J. FROST,
W. N. WILLIAMS.
